(57) **CLAIM**

The ornamental design for a bird feeder water fountain, as shown and described.

DESCRIPTION

FIG. 1 is a perspective view of a bird feeder water fountain showing the new design;

FIG. 2 is a front view of the bird feeder water fountain of FIG. 1;

FIG. 3 is a rear view of the bird feeder water fountain of FIG. 1;

FIG. 4 is a right side view of the bird feeder water fountain of FIG. 1;

FIG. 5 is a left side view of the bird feeder water fountain of FIG. 1;

FIG. 6 is a top view of the bird feeder water fountain of FIG. 1; and,

FIG. 7 is a bottom view of the bird feeder water fountain of FIG. 1.

In the accompanying drawings, the evenly-spaced broken lines in the figures depict portions of the bird feeder water fountain that form no part of the claimed design.

1 Claim, 7 Drawing Sheets
